UNITED STATES PATENT OFFICE.

HERON McCAMPBELL, OF HOLMDALE, NEW JERSEY.

DRESS PATTERN.

Application filed December 14, 1922. Serial No. 606,802.

The present invention relates to certain new and useful improvements applicable to tailor's guides, garment maker's templets and patterns, but more particularly useful and valuable in connection with the cheap patterns generally made of paper and sold in great numbers to dressmakers and to women generally for use in the shaping and assembling of garments of all kinds.

It has been generally customary hitherto to put out a separate paper pattern for all the parts of each size of each different design and kind of garment; and for the sake of cheapness and to facilitate cutting many patterns at once, very thin and flimsy cheap paper has generally been used for this purpose. As the number of designs of each kind of garment is always very great, and, as every design must be supplied for many different sizes, this system makes it necessary for each dealer to meet competition by keeping in stock an immense number of patterns, even if he keeps only a few of each design, size and kind. Since styles are constantly changing and the number of dealers handling patterns is very great, it follows that each manufacturer of patterns is obliged to keep up a tremendous volume of output, a large part of which is never used. The amount of capital thus tied up is, therefore, very large.

If this system could be modified in a manner to permit each pattern for a given design to be available for any size of garment made in that design, it is clear that a saving of very great value would be achieved. The volume of unused patterns would be greatly reduced, the capital tied up in stock manufactured and stock kept on hand by dealers would be greatly lessened, and the convenience of the customers would be enhanced. Furthermore, this saving would make it possible to use thicker and better paper and thus to produce more durable patterns of a nature more easily handled by the user.

Another advantage resulting from such a system would be that the peculiarities of each individual's figure could be accommodated in a manner that is at present not practically possible. For instance, women's waists are identified as to size by the bust measurement, and it is assumed that, a given bust measure corresponds in each individual to certain other bodily measurements. Such is far from the case, however. For instance a round shouldered flat chested person would

require a pattern for the back that corresponded to a large bust measurement, while, of course, the front of the pattern for that bust measure would be a misfit.

If, however, the pattern for each design is prepared in multiple form on a single sheet, so arranged that the user has her choice of sizes before her; or may, if she pleases, cut her pattern with more or less fulness here or there, she can get a better individual fit with no extra care or expense. For instance, a round shouldered and flat chested woman would simply cut the back of her waist from say a number forty two and the front from say a number thirty eight. Other peculiarities of figure could be similarly accommodated. Among these may be mentioned the wide variations in hip measurement and sizes of arms found among women of the same bust measure. Children are even more variable in their proportions than adults and the present system of grading by the supposed average sizes at various ages leaves much to be desired.

For instance, a child might require an eight years size for the breast measure and might be so tall as to require a ten years size for the skirt. An approximation to the requirements of such a case might be had by purchasing two complete patterns, one for the eight years size and one for the ten years size, but this would entail a double expense and, as the skirt of one pattern was not intended to go with the waist of the other, good results would not be had.

One aspect of the present invention contemplates printing or otherwise marking the outlines for a number of sizes on a single pattern sheet. In such a pattern there would be a common meeting point for all sizes and the different sizes of the different parts would be designed to go together at the respective common points. Different sizes in the different parts of a garment might thus be used, with such slight modifications as would be within the limits of seam allowances.

In shaping the material to fit the human form it is often necessary to cut out portions of surplus material. Darts, for instance, are used in this way in a sleeve, to accommodate the curve of the arm. The position, width and depth of such a dart would vary with each size in a given garment part, and, where a number of sizes are outlined on one pattern sheet, it would cre-

ate an impractical degree of confusion to attempt to mark the darts of all the sizes on a single sheet.

In order to secure the great advantages resulting from having a number of sizes shown on a single pattern sheet, and still avoid the confusion that would result from marking all the various corresponding sizes and locations of the darts for these different sizes, the present invention contemplates providing the main outlining sheet for each garment part with an auxiliary strip for each size of garment part outlined thereon, said strips bearing marks indicating exactly where the dart or darts for the corresponding size should come when the strip is laid across the material. These strips may be supplied separated from the outline sheets to which they belong, or they can be formed integrally therewith, and be cut off by the user. Such a dart strip can be made for one or both sides of a garment part, and be prepared either for full length (or width) or half length (or width) as may be desired. Another kind of finishing much in vogue for women's and children's garments is the application of trimming, braiding, or the cutting out of scallops or other shapes. The sizes and positions of scallops and the like vary with different sizes, and the positioning of trimmings etc. also varies according to size. Obviously, therefore, it would lead to hopeless confusion to attempt to indicate details of this kind for various sizes on a single sheet. The special cutting for preferential neck lines (high, low, round, oval, or V) may be shown in the same manner upon separate or separable auxiliary strips, and these strips may be used after the main outline is cut in the same manner as "dart" or "scallop" strips. Indeed, the invention applies to the use of auxiliary strips adapted to guide the dressmaker in any kind of selective finishing after the main outlining has been accomplished, whether for accommodating variations in size or to make it possible to select any one of a number of designs for the finish of the particular garment part in hand.

The present invention contemplates the provision of one or more auxiliary strips for each size which bear upon them the necessary guide marks for the location of any kind of finishing for its own size; so that, when laid across or along the edge of the outline pattern for that size, it will indicate just where cuts are to be made for gussets, darts etc. or where trimmings are to be applied or scallops or other finishings are made or applied. The invention is not limited to the use of auxiliary strips for any particular kind of finishing, but includes all. A given pattern may be provided either with auxiliary strips for only one kind of finishing for each size, or with strips for

different kinds of finishing; and in any case the strips may either be formed integrally with an outlining sheet or be sold separated therefrom. Of course, if desired, more than one kind of finishing may be shown on a single strip.

The invention is not limited to the use of auxiliary strips in connection with outlining sheets showing a plurality of sizes. In most cases, patterns for only one size are intended to be used for marking or stitching through perforations, the locations of certain finishings. This entails trouble in making and in erasing the marks, and in using certain delicate fabrics marks of this kind are actually so damaging to the material. By using the auxiliary separate or separable strips to lay across the fabric when cut to the desired outline, these objections are avoided.

Another advantage of using auxiliary folding strips with a one-sized garment pattern is that it makes it possible, by supplying a number of strips, to select any one of a number of kinds, sizes or relative locations of finishing.

The invention is illustrated in the accompanying drawings in connection with a main outlining pattern sheet for one part of a garment marked for three sizes. Only three sizes are indicated for greater clearness in the drawing, although it is to be understood that the invention is to be applied to patterns for only one size or for as many sizes as are found convenient. Also the outlines etc. may be either perforated or printed, although the latter, as illustrated, is preferred, since, among other advantages, it permits both sides of a pattern sheet to be separately used, thus permitting the display of a greater number of sizes than would otherwise be possible.

It is to be understood that these figures are merely explanatory of the principles of the invention, and that the actual proportions and locations of guide lines shown are not intended to be correct in any given pattern. In other words, no attempt is here made to show a properly graded pattern for actual use, as this is a matter within the province of those skilled in the art.

Also it is to be understood that, although, for greater clearness and simplicity, only one auxiliary strip is shown in the drawing for each size, the invention applies to patterns in which, for instance, two strips are given for each size, one for a finishing or shaping at one part (say the neck) and the other at another part (as along the bottom). In other words, the number of strips supplied for each size is not an essential of the invention.

The patterns made in accordance with this invention may be either full size; or, as is frequently the case in present practice, they may correspond to one half of the symmetri-

cal garment part for which each is intended. The auxiliary strips, too, may be made either half length or full length, or any length desired.

5 In the drawings, Fig. 1 shows a half width outlining sheet for a woman's waist in three sizes, Figs. 2, 2^a and 2^b show auxiliary dart strips for the three sizes respectively, and Fig. 3 shows a half width outlining sheet for 10 a skirt with attached auxiliary strips for scallops for three sizes.

In Fig. 1 the outlining sheet is shown bounded on one side by the straight center fold line, and on two other sides by the 15 line 11 corresponding to the largest sized waist contemplated. The line 12 indicates the next smallest size and the line 13 the smallest of the three sizes intended.

In order to shape the garment to the figure, taking it in at the waist, a dart (generally triangular) is cut out of the cloth at the 20 proper point along the lower edge 14. The size and location of the dart will vary with the garment size; and, generally, a larger 25 dart will be taken from a smaller waist and vice versa. Accordingly strips such as shown in Figs. 2, 2^a and 2^b will be supplied, bearing the marks 15, 16 or 17 respectively, which indicate the location and size of the 30 darts to be removed, when the left hand edge of the strip is applied to the center fold of the cut out garment. Fig. 2 shows the strip for the smallest sized waist, Fig. 2^a for the next size and Fig. 2^b for the largest.

35 By placing such a strip flat against the single cloth, after outlining by means of the sheet shown in Fig. 1, and properly locating the strip as per directions supplied in any manner, the dart can be accurately and 40 easily made by cutting through the strip and cloth together.

In Fig. 3 is shown a half width skirt outlining sheet, whose straight center fold line is shown at 18. The lines 19, 20 and 21 limit 45 the width of the half pattern for three sizes.

The auxiliary strips are here shown, formed integral with the pattern and bearing lines to guide in the cutting out of appropriate scallops for the different sizes. 50 Strip 22 is for use with the largest size, strip

23 with the next smaller size and strip 24 with the smallest size. It is, of course, immaterial whether these strips be straight, curved or, indeed, how they are shaped. Proper directions of any well known character being supplied, the strip proper for a given size which has been cut out can be applied against the cloth and, by cutting paper and cloth together along the guiding line or lines, the scallop (or other shaping or finishing) can be accomplished. In the claims the term "finishing" includes shaping by cutting or otherwise.

In a copending application for patent, Serial No. 606,803, filed December 14, 1922, 65 the use of auxiliary strips for guiding in pleating, tucking, smocking, etc. is shown and claimed and this specific use of the idea is therefore not herein set forth and claimed.

70 What is claimed is—

1. In a pattern for a garment part a sheet bearing the outline of a garment part of specific shape and size, in combination with an auxiliary strip bearing guiding outlining 75 marks adapted, when laid on said outlined garment part, to indicate the required position and size of the finishing cuts for that specific size and shape of the garment part.

2. Means for insuring the proper finishing 80 cutting of a shaped garment part of a specific shape and size comprising a strip of material bearing guiding marks and adapted, when properly located on said garment part to indicate clearly to a dressmaker the 85 location of the finishing cuts required by said specific shape and size of garment part.

3. As an article of manufacture a sheet having printed upon it the outlines of garment parts of specific sizes and also having 90 printed upon it the outlines of guiding strips each of which strips bears guiding marks adapted to clearly indicate to a dressmaker the location of the finishing cuts required in the garment parts shaped like the respective 95 outlines of garment parts on said sheet.

In testimony whereof I have hereto set my hand.

THERON McCAMPBELL.
